United States Patent Office

Des. 234,104
Patented Jan. 21, 1975

234,104

CHAIR

Morris F. Fisher, 9820 Deerfield Circle,
Carmel, Ind. 46032

Filed June 1, 1973, Ser. No. 366,232

Term of patent 14 years

Int. Cl. D6—01

U.S. Cl. D6—42

The figure is a perspective view of a chair illustrating my new design.

The back of the chair is conventionally plain while the side not shown is substantially identical to the side shown.

I claim:

The ornamental design for a chair, as shown.
